J. BIJUR.

IGNITION SYSTEM.

APPLICATION FILED JUNE 7, 1919.

1,362,386.

Patented Dec. 14, 1920.

INVENTOR
JOSEPH BIJUR

BY *John G. Davis*

ATTORNEY

UNITED STATES PATENT OFFICE.

JOSEPH BIJUR, OF NEW YORK, N. Y., ASSIGNOR TO BIJUR MOTOR APPLIANCE COMPANY, A CORPORATION OF DELAWARE.

IGNITION SYSTEM.

1,362,386.

Specification of Letters Patent. Patented Dec. 14, 1920.

Application filed June 7, 1919. Serial No. 302,479.

To all whom it may concern:

Be it known that I, JOSEPH BIJUR, a citizen of the United States, residing at New York city, in the county of New York and State of New York, have invented certain new and useful Improvements in Ignition Systems, of which the following is a clear and exact description, such as will enable others skilled in the art to which it appertains to make and use the same.

This invention relates to ignition systems and to apparatus therefor.

One of the objects thereof is to provide a system of the above type which shall be reliable in action, which shall have a relatively long period of usefulness and which shall require little attention.

Another object is to provide a system of the type referred to which shall produce a relatively hot ignition spark, effectively avoiding however, a rapid wear of the breaker contacts.

Other objects will be in part obvious and in part pointed out hereinafter.

The invention accordingly consists in the features of construction, combination of elements and arrangement of parts which will be exemplified in the construction hereinafter set forth, and the scope of the application of which will be indicated in the following claims.

Referring now to the accompanying drawings wherein is shown one of various possible embodiments of the several features of this invention, Figure 1 is a diagrammatic view of one embodiment of my invention, and Fig. 2 is a detailed view showing the correct relative disposition of certain of the parts indicated in Fig. 1.

Similar reference characters refer to similar parts throughout the different views of the drawings.

Referring now to the drawings I have indicated a generator 1 of the type adapted to motor vehicles, the main brushes 2 and 3 of which are connected to mains 4 and 5 across which there is disposed a suitable storage battery 6 of the type employed on motor vehicles. By way of illustration I have shown a generator of the third-brush type, the field coil 1' thereof connecting an extra brush 2' displaced from neutral to the main 5.

The battery 6 is preferably connected to the generator through the series coil 7 of an

automatic switch 8 biased to open position by spring 13, the said switch having a shunt coil 9 connected across the mains 4 and 5. As my invention does not reside in the automatic switch *per se*, it may be briefly noted that when the generator produces the proper voltage, coil 9 will cause the closure of switch 8 overcoming the retractile spring 13 so that the generator is directly connected in charging relation to the storage battery 6, and is furthermore connected in parallel with the battery to pass current to lamps 11 or other translating devices, which may be placed in circuit by closing the corresponding switches 12.

Connected across the mains 4—5 I have diagrammatically shown an ignition circuit comprising a primary coil 14 having in series therewith a breaker 15, the said breaker comprising a cam 16, a breaker arm 17 coöperating therewith and breaker contacts 18—19, the former stationary, and the latter carried by the arm 17. Connected across the breaker contacts I preferably provide the usual condenser 32. I have indicated at 20 the secondary coil inductively related to the primary 14, and connected to a spark-plug 21. It is to be understood that the invention does not reside in the details of the ignition circuit so far described, taken by itself, and it should be noted that either a separate coil may be used for each spark-plug or a single coil and distributor may be employed.

In proximity to breaker contacts 18—19 I provide a magnetic blow-out comprising preferably a horse shoe magnet core 22 having poles 23, 24 in close proximity to, and at opposite sides of the gap 25 between contacts 18 and 19 when separated. The poles are preferably so related that the magnetic flux across the air gap 25 intersects the spark 26 between the said contacts substantially at right angles. The energizing element of the magnetic blow-out is a coil 27 encircling core 22 and connected to the mains 4 and 5.

It is desirable to have the blow-out coil continuously energized during the operation of the engine, avoiding, however, needless depletion of the battery 6 therethrough when the apparatus is not operating. For this purpose I preferably provide a switch 28 controlling the circuit of blow-out coil 27, the said switch being interlocked as in

dictated diagrammatically at 29 with the ordinary ignition switch, diagrammatically indicated at 30.

Assuming the engine is set into operation 5 my system functions as follows: When the generator 1 has built up sufficient voltage to cause coil 9 to attract switch 8 the charging current will be conducted to battery 6, and current will be led from the generator 10 and the battery in parallel to the translating devices 11, and, switch 30 being closed, to the ignition primary coil 14, as well as to the magnetic blow-out coil 27.

At each separation brought about by cam 15 16 between contacts 18 and 19 the magnetic blow-out 22 will function to interrupt the arc ordinarily occurring between said contacts, such arc extending as shown in Fig. 2 across the flux indicated by arrows between poles 23 and 24. This action takes 20 place according to the well known operation of magnetic blow-outs, the arc being first deflected in a direction at right angles to both the magnetic flux and the direction of 25 current flow. As a consequence the arc will be rapidly attenuated and interrupted causing a sharp break-down of the flux in the primary coil and consequently inducing a relatively high electromotive force in the 30 secondary, resulting in a relatively hot ignition spark.

The spark or arc of appreciable duration, which may occur between the primary contacts in the absence of my blow-out or the 35 equivalent thereof constitutes a continuation of the current flow in the primary circuit after the breaker contacts 18, 19 are separated. The break-down of the magnetic flux is thus slower, and the electromotive 40 force induced in the secondary is less than with my magnetic blow-out. By the use of my blow-out I thus secure a hotter ignition spark.

By virtue of the short duration of the 45 spark between the primary contacts, the rate of pitting of said contacts is diminished, and the amount of attention and service required is lessened.

It should further be noted that in case 50 the condenser should break down in operation my blow-out will render continued operation of the ignition system possible with reasonable efficiency and will effectively prevent destruction of the breaker 55 contacts.

Although I have by way of illustration set forth my invention as applied to a motor vehicle it is to be understood that it is applicable with beneficial results to stationary 60 engines. It is also apparent that the invention is not limited to ignition systems employing a battery as shown and described but has utility in any high tension ignition system whether of the magneto or battery

type. It is also to be understood that the 65 circuit shown in the drawings as of the "two-wire" type is merely illustrative and that the invention may be carried out in a "single-wire" or grounded application.

It will thus be seen that there is herein 70 described apparatus in which the several features of this invention are embodied, and which apparatus in its action attains the various objects of the invention and is well suited to meet the requirements of practical 75 use.

As many changes could be made in the above construction and many apparently widely different embodiments of this invention could be made without departing from 80 the scope thereof, it is intended that all matter contained in the above description or shown in the accompanying drawings shall be interrupted as illustrative and not 85 in a limiting sense.

Having thus described my invention, what I claim as new and desire to secure by Letters-Patent is:

1. In an ignition system, in combination, a source of current, a pair of breaker contacts, a condenser or the like, connected across said contacts, and a magnetic blow-out having a coil connected to said source of current and having two poles one on each side of said pair of breaker contacts, 95 whereby the flux of said blow-out will intersect the residuary spark between said contacts at right angles.

2. In an ignition system, in combination, a storage battery, a primary coil and a pair 100 of breaker contacts in series therewith, said elements being connected across said battery, a condenser or the like connected across said contacts, a magnetic blow-out for interrupting the residuary spark between said contacts, said blow-out having a coil electrically connected across said battery, means for disconnecting said ignition circuit from said battery, and means for preventing energization of said blow-out coil, when said 110 ignition circuit is disconnected.

3. In an ignition system, in combination, a storage battery, a primary coil and a pair of breaker contacts in series therewith, said elements being connected across said battery, a condenser or the like connected across said contacts, a magnetic blow-out for interrupting the residuary spark between said contacts, said blow-out including an energizing coil connected across said battery, a 120 switch for closing said ignition circuit, and a second switch interlocked therewith for simultaneously connecting said blow-out into operative condition.

In testimony whereof I have signed my 125 name to this specification this 2nd day of June, 1919.

JOSEPH BIJUR.
